By their Attorney,
Cochran Crosby

UNITED STATES PATENT OFFICE.

JOSEPH ALLEN JOHNSON, OF NIAGARA FALLS, NEW YORK, AND HARRY M. KING,
OF NIAGARA FALLS, ONTARIO, CANADA.

ELECTRICAL SWITCH.

Application filed July 18, 1919. Serial No. 311,773.

To all whom it may concern:

Be it known that we, JOSEPH ALLEN JOHNSON and HARRY M. KING, both citizens of the United States, and residents of Niagara Falls, Niagara County, State of New York, and of Niagara Falls, Ontario, Canada, respectively, have invented certain new and useful Improvements in Electrical Switches, of which the following is a specification.

Our invention relates to improvements in electrical switches and more particularly to that type known as disconnecting switches for high potential alternating current circuit or circuits of large current capacity in which the switch is adapted to be opened and closed manually by means of a separate insulated hook handle. Such switches are particularly useful in stations employing alternating current at high potential for isolating oil switches and other apparatus and at present the type of switch known as the knife switch is commonly used, which consists of one or more blades of hard copper hinged at one end and slipping over or between stationary blades or jaws at the other end, this type of switch being similar to switches of small size which have been commonly used in circuits of low voltage and small capacity.

In high potential alternating current systems or circuits of large current capacity of relatively low voltage, this knife switch is open to the objection that in large sizes they are difficult to operate, difficult to fit, adjust and maintain, or become worn out or lose capacity with age. They are also costly to manufacture on account of the great skill and care required in fitting and adjusting and in stations of large capacity, it is necessary to equip them with special latches to prevent them from being thrown open by heavy short circuit currents.

According to our invention we provide a switch in which the connecting switch member is of the brush type, preferably made of a series of spring copper layers or laminations in the form of an arch suitably clamped together and supported, and arranged to be forced against the contact terminals and maintained in electrical contact thereagainst under pressure. We are aware

that the brush type of switch has been used for oil switches and circuit breakers operated automatically, but so far as we are aware we are the first to point out the advantage of using such brush type switch member in disconnecting switches where high potential or large alternating currents are used and the switch is adapted to be opened and closed manually by means of an insulated handle. We find that by using a brush type switch means in a disconnecting switch adapted to be so operated, the operation is not only easy but the necessary pressure to make proper contact may be applied simply by means assuring certainty of contact. In such an arrangement the fitting and adjustment is easy and no grinding is necessary as is the case with knife contact switches. As the wiping action between contacts of this character is very slight the wear is small and if any takes place the contacts may be easily dressed and readjusted without loss of capacity. Furthermore, in the larger type of switches the cost of production is materially less and the heavy currents carried do not need to pass through the hinge or supporting element of the moving switch member, so that the hinge or pivot need not be of a tight fit and the switch may be easily constructed and so that the moving parts can be removed without killing the circuit, thereby permitting the removal of the moving switch parts for adjustment and repair while the switch contacts are alive. Further objects, features and advantages will more clearly appear from the detail description given below taken in connection with the accompanying drawings which form a part of this specification.

Referring to the drawings Fig. 1 is a side elevation, partly in section, of a switch embodying my improvements in a preferred form thereof. Fig. 2 is a view taken at right angles to that shown in Fig. 1 of the main switch apparatus. Fig. 3 is a transverse section taken on the line 3—3 of Fig. 1. Fig. 4 is a transverse section taken substantially on the line 4—4 of Fig. 1. Fig. 5 is a transverse section taken on the line 5—5 of Fig. 1. Fig. 6 is a perspective of the lever cam member for closing the switch

2
shown in Fig. 1, and, Fig. 7 is a detail illustrating a modified arrangement for adjusting the brush switch contact means.

Referring to the drawings and more particularly to Figs. 1 to 6 inclusive, 8, 8 represent suitable high potential insulators adapted to carry 2,000 volts or more and supporting base members 9 which are suitably insulated from one and the ground 10 ground by the insulators 8. Secured to the upper supporting member 9 is an electrical copper contact 10 and secured to the lower supporting member 9 is another electrical copper contact member 11. Suitable connections to the circuit are made to the contact members 10 and 11 by means of terminal members 12, 13, 14 and 15 and nuts 16. Secured to the supporting member 9 by means of bolts 17, which also secure the contact 11 20 to the base 9, is a lug or projecting member 18 provided with a vertical slot 19. (See also Fig. 5.) 20 represents a suitable frame provided at its lower end with a pivot 21 screwed thereinto. The pivot 21 is adapted 25 to be dropped into the slot 19 so that the frame 20 is pivotally supported upon the lug 18. In order to hold the pivot 21 in its bearing slot 19, we provide a screw 22 adapted to be screwed laterally into the end 30 of the lug 18 and having its inner end 23 extend over or past the pivot 21 so as to keep it in the slot 19. Pivotally mounted to the frame 20 and centrally thereof is a cradle 24 (see also Fig. 4) and operating in 35 the cradle 24 is a screw member 25, one end of which is provided with left hand threads and the other end of which is provided with right hand threads, one end of which operates in the cradle 24 and the other in a member 26 to which is secured by bolts 27, a brush switch member 28 composed of a series of spring copper sheets or laminations, the brush ends of which are adapted 40 to abut against and make electrical contact with the contact members 10 and 11 as clearly 45 shown in Fig. 1. At the center the brush means 28 are provided with a central opening 29 through which a screw driver with an insulated handle may be inserted in order 50 to turn the screw member 25 and so move the brush switch member 28 toward and from the contacts 10 and 11 and with respect to the cradle 24 and frame 20 which carries the same. It will be noted that the spring 55 copper laminations composing the switch brush member 28 are clamped between the members 26 and 30 by means of bolts 27 to form a fairly rigid switch means which is adjustably carried by the cradle 24 which is 60 adapted to rock slightly so that both ends of the brush switch will automatically adjust themselves to bear firmly against the contact members 10 and 11 respectively when the switch is closed. Nevertheless the frame 65 has a positive connection with the cradle

and brush switch through the screw 25 so that the frame will positively force and press the switch against the contacts without permitting any yielding movement of the switch as a whole toward the frame due 70 to the pressure of the switch against the contact members.

In order to close the switch I provide at its upper end a lug or member 31 secured to the upper base support 9 by bolts 32 which also secure the upper contact 11 to the base member 9 (see also Fig. 3). 33 represents a lever cam member (see also Fig. 6) provided with pivot pins or extensions 34, one on either side which extend into and operate 80 in vertical slots 35 in the upper ends of the sides of the frame 20. The lug 31 is recessed on its underneath side as shown by dotted lines 36 in Fig. 1 and the member 33 is provided with a cylindrical portion 37 extending between its ends which member 37 is arranged eccentric to the pivot extensions 34 and is adapted to engage the recess 36. The member 37 preferably extends through the ends of the member 33 and has integral 90 therewith the pivots 34, all of which is made rigid with the body part of member 33 by keys 38 so that all parts shown in Fig. 6 are held rigidly together. A bolt 39 extends across the frame 20 at its upper end as 95 shown in Figs. 1 and 2 and the side members of the member 33 are recessed at 40 to accommodate this bolt. The ends of the member 33 are also recessed at 41 for a purpose to be more clearly hereinafter described. With the parts in the positions shown in Fig. 1 it will be seen that the eccentric 37 engaging within the recess 36 prevents the frame 20 from being swung outwardly to the right as viewed in Fig. 1 to 105 open the switch. When, however, it is desired to open the switch a hook with an insulated handle may be inserted within the hole 42 in the end of the member 33 and the lever member 33 swung counterclockwise as 110 viewed in Fig. 1 so that the eccentric member 37 will be rotated in the recess 36 and the pivot members 34 be swung slightly outwardly thereby causing the upper end of the frame 20 to be moved outwardly in a clockwise direction as viewed in Fig. 1 to a slight extent. The lever member 33 will be moved substantially to the position indicated in dotted lines at the top of Fig. 1 whereupon 115 it may be dropped or pulled down vertically so that the recesses 41 will engage the bolt 39. By thus moving the member 33 downward vertically the eccentric 37 is also pushed down out of the recess 36 so that the eccentric 37 is moved free and clear of the lug 31, whereupon by means of the insulated handle having means engaging aperture 42, the switch may be pulled open in the usual way. During such movement the member 33 120 will be held rigid with the frame 20 by 130

reason of the bolt 39 (which is rigid with the frame 20) being engaged within the recesses 41 of the member 33 thereby preventing any rotation of the member 33 with 5 respect to the frame 20.

When it is desired to close the switch the insulated handle, which may be permanently secured to the member 33 or provided with a hook adapted to be inserted in the aperture 42, is manually operated to swing the brush switch member with all its parts about the pivot 21 to the position where the member 33 will be in the position shown in the dotted line at the top of Fig. 1. Thereupon the member 33 is pushed upwardly with the insulated handle so that the bolt 39 is removed from the recesses 41 and then by means of the insulated handle engaging the aperture 42 the member 33 is swung about 10 the projections 34 as an axis, in a clockwise direction as viewed in Fig. 1, so that the eccentric 37 will engage within the recess 36 and by reason of the cam action of the eccentric 37 against the outer face of the recess 15 36 the member 20 will be forced toward the switch contacts 10 and 11 thereby moving the brush 28 toward the switch contacts 10 and 11, and the brush ends into electrical contact with the contact faces of the contacts 20 10 and 11. By allowing the eccentric 37 to swing slightly past the dead center the brush switch member is automatically held firmly up against the contacts 10 and 11 and the switch automatically locked closed with the 25 brush ends bearing against the contacts 10 and 11 under pressure. At the upper end the side members of the frame 20 are provided with projecting lugs 50 which act as stops for the member 33 when it is moved 30 slightly beyond the dotted line position shown in the upper part of Fig. 1.

It will be seen from the above that the switch may be opened and closed and locked closed in a most simple and efficient manner 35 by means of the usual insulated hook handle connected to the lever member 33, which not only is adapted to serve as a means for closing the switch by cam or eccentric action, but also as a means for holding the switch 40 closed under pressure. Should it be desirable to remove the moving elements of the switch for inspection or repair, this is very easily done by opening the switch in the manner above described and then by means 45 of a screw driver with an insulated handle removing the screw 22 whereby the frame 20 with its pivot 21 and all connected parts may be easily slipped out and removed to a safe distance from the switch contacts 10 and 11. In this type of switch it will be further 50 noted that the main current carrying contacts are entirely separate from the mechanical devices for hinging and holding the switch member in closed position.

65 Referring to Fig. 7 I there show a modi-

fication in which the adjustment of the brush member is obtained in a somewhat different manner. In Fig. 7 the cradle 24 is reversed and a screw 60 is threaded therein which screw has at one end a reduced non-threaded portion 61 passing through the member 30, brush 28 and member 26 with a nut 62 at its outer end. A spring washer 63 is inserted between a nut 62 and the member 26, and a washer 64 is 70 shown between the screw threaded portion 60 and the clamping member 30. A lock nut 65 is provided on the member 60 on the outside of the cradle 24. When it is desired to adjust the brush 28 laterally with respect 75 to the cradle 24, the nut 65 is loosened and with a screw driver with an insulated handle, the screw 60 is turned thereby moving the brush 28 and members 26 and 30 laterally with respect to the cradle 24 and 80 toward or away from the electrical contacts 10 and 11. When adjusted to the desired 85 position the lock nut 65 may be again screwed into place.

It will also be understood that many 90 other changes and modifications may be made without departing from the spirit and scope of the invention in its broader aspects. Consequently we desire to cover all forms coming within the terms of the appended 95 claims and their equivalents.

What we claim and desire to secure by Letters Patent is:—

1. In an electric switch the combination of two electrical contact members, a frame 100 pivotally mounted adjacent the first contact member and so as to swing with respect to both contact members, a brush type switch mounted on said frame adapted to electrically connect said contact members when the frame is swung to close the switch, means adjacent the second contact member and means on the frame adjacent the end thereof opposite its pivot and cooperating with said last mentioned means to hold the 105 switch closed.

2. An electric switch of the class described and adapted to be opened and closed manually having in combination, two electrical contact members, brush type switch 110 member adapted to electrically connect said contact members, a pivot for said switch member, a member provided with a slot into which said pivot is inserted to pivotally mount the switch member with respect to said contact members, and means holding said pivot in the slot but adapted to be operated to permit the removal of the pivot 115 from the slot to permit removal of the switch member.

3. An electric switch having in combination two electrical contact members, a brush type switch member pivotally mounted with respect thereto, means for closing said switch member to thereby electrically con- 120 125 130

nect said contacts, a slotted member, said switch member having a pivot normally operating in a slot in said slotted member and removable means retaining said pivot in said slot.

4. An electric switch of the class described and adapted to be opened and closed manually by means of an insulated handle, having in combination, two electrical contact members, a switch member comprising a frame and a copper brush switch means carried thereby and adapted to contact with said contact members, means whereby said frame is movable relatively to said contact members to close and open the switch and means for adjusting said copper brush switch means toward and from the said contact members and with respect to the frame, said last mentioned means comprising a member interposed between said frame and brush switch and pivoted with respect to one and adjustable to and fro with respect to the other, and a screw with series of right and left handed threads thereon, one series operating in the switch and the other in said interposed member.

5. An electric switch of the class described and adapted to be opened and closed manually having in combination, two electrical contact members, a switch member comprising a frame and a copper brush switch means carried thereby and adapted to contact with said contact members, means whereby said frame is movable relatively to said contact members to close and open the switch and means for adjusting said copper brush switch means toward and from the said contact members and with respect to the frame, pressure means mounted on and supported by said frame for causing the brush ends to engage said contact members under pressure and holding them in contact with said contact members under pressure and means whereby said last mentioned means may be operated by a separate insulated handle.

6. An electric switch for high potential currents and adapted to be opened and closed manually by means of an insulated handle, having in combination, two electrical contact members, high potential insulating means supporting said contact members, a frame pivoted with respect to said contact members and also supported by said insulating means, a cradle carried by said frame and adapted to have a rocking movement with respect thereto, copper brush switch means carried by said cradle and adapted to make electrical contact with said contact members, means for adjusting said brush switch means toward and from said contact members and with respect to said frame, means including a lever and cam also supported through said insulating means and adapted to mechanically move said

frame to press the brush contacts against the contact members to close the switch and hold it in closed position under pressure.

7. An electric switch having in combination, two electrical contact members, a frame pivoted with respect thereto, a brush type switch carried by the frame and adapted to electrically connect said contact members when the frame is moved to close the switch, screw threaded means for adjusting the switch on the frame in a direction toward and away from the contact members when the switch is closed, and the switch being connected with the frame such that the frame will positively force and press the switch against the contact members without permitting any yielding movement of the switch as a whole toward the frame due to the pressure of the switch against the contact members.

8. An electric switch for high potential currents and adapted to be opened and closed manually by means of an insulated handle, having in combination two electrical contact members, high potential insulating means separately supporting said contact members, a frame movable with respect to said contact members, a brush type switch carried by the frame and adapted to electrically connect said contact members when the frame is moved to close the switch, screw threaded means for adjusting the switch on the frame in a direction toward and away from the contact members when the switch is closed, and the switch being connected with the frame such that the frame will positively force and press the switch against the contact members without permitting any yielding movement of the switch as a whole toward the frame due to the pressure of the switch against the contact members under pressure.

9. An electric switch of the class described, having in combination two electrical contact members, a brush type switch member pivotally mounted with respect to said contact members, means fixed with respect to the said contact members and means mounted upon said brush type switch member and disengaged from said fixed means when the switch is open and adapted to engage said fixed means to cause the brush ends to be forced against the two contact members and maintained thereagainst under pressure.

10. An electric switch of the class described, having in combination two electrical contact members, a brush type switch member pivotally mounted upon one of the said contact members, a projecting member mounted upon the other of the two contact members and means mounted upon said brush switch member adapted to mechanically engage the said projecting member to

cause the brush ends to be forced against the two contact members and maintained thereagainst under pressure.

11. An electric switch of the class described, having in combination two electrical contact members, a brush type switch member pivotally mounted with respect to the said contact members, a projecting member fixed with respect to the said contact members and means mounted upon the free end of the said brush switch member and carried thereby and adapted to engage said projecting member to cause the brush ends to be pressed against the two contact members and maintained thereagainst under pressure.

12. An electric switch of the class described, having in combination two electrical contact members, engaging means fixed with respect to said contact members, a brush type switch member pivotally mounted with respect thereto, said switch member containing a slot and means mounted upon the brush switch member and movable with respect thereto and adapted to operate in said slot and engage said engaging means to cause the brush ends to be forced against the contact members and maintained thereagainst under pressure.

13. An electric switch of the class described, having in combination two electrical contact members, a brush switch member pivotally mounted with respect thereto, an eccentric with a lever attached thereto, pivotally mounted in a slot in the said switch member and adapted to be both rotated and moved longitudinally in said slot, means fixed with respect to the said contact members and containing a slot open at one end, the said parts being positioned so that the said eccentric may be made to engage the slot in the said means and upon being rotated therein by means of the said lever, will cause the brush ends to be forced against the two contact members and there maintained under pressure.

14. An electric switch of the class described, having in combination two independent and separate insulating supports fixed relatively to each other, two contact members mounted respectively upon said insulating supports, two projecting members mounted respectively upon the two contact members, a brush switch member pivotally mounted upon one of the said projecting members and means mounted upon the said switch member adapted to engage the other projecting member to cause the brush ends to be drawn against the two contact members and there maintained under pressure.

15. An electric switch of the class described, having in combination two electrical contact members, a frame pivotally mounted at its lower end with respect thereto to swing toward and away from the contact members

in a plane substantially at right angles to the contact surfaces of the contact members, a switch adjustably mounted upon said frame, means for adjusting said switch relatively to said frame, said switch being adapted to contact with said contact members, and means carried by said frame at the upper end thereof for causing said brush switch means to be drawn into contact with said contact members and there held under pressure and adapted to be manipulated by means of an insulated hook stick.

16. An electric switch of the class described, having in combination two electrical contact members, a frame pivotally mounted with respect thereto, brush switch means mounted upon said frame, a movable member mounted upon said frame adapted to cause the brush switch means to be drawn into contact with the said contact members and means whereby the said movable member may be made to become rigid with respect to the said frame whereby it may be used as a handle for the manipulation of the said frame and brush switch member in closing and opening the switch.

17. An electric switch having in combination, two electrical contact members, a switch member pivotally mounted with respect to said contact members and adapted to be swung about its pivot to electrically connect said contact members, means fixed with respect to the contact members and a device pivotally mounted on the switch member and disengaged from said last mentioned means when the switch is open but adapted to engage said fixed means on closing the switch and with a cam action cause the switch member to be forced against the contact members.

18. An electric switch having in combination, two electrical contact members, a switch member pivotally mounted with respect to said contact members and adapted to be swung about its pivot to electrically connect said contact members, means fixed with respect to the contact members and a device pivotally mounted on the switch member and disengaged from said last mentioned means when the switch is open but adapted to engage said fixed means on closing the switch and with a cam action cause the switch member to be forced against the contact members, and means whereby said device may be prevented from having pivotal movement on said switch member.

19. An electric switch having in combination, two electrical contact members, a switch member pivotally mounted with respect to said contact members and adapted to be swung about its pivot to electrically connect said contact members, means fixed with respect to the contact members and means on the switch member adapted to cooperate with said first means to hold the

switch closed, one of said means including a pivotally mounted member adapted to engage the other means with a cam action to force the switch closed, the carrying of the cam past dead center acting to lock the switch in closed position.

Signed at Niagara Falls, in the county of

Niagara and State of New York, this 15th day of July, 1919.
